HINGE CLIP FOR EARRINGS

Georges Ebertin, 562 5th Ave., New York, N.Y.

Filed Oct. 28, 1959, Ser. No. 58,099

Term of patent 14 years

(Cl. D45—1)

FIG. 1

FIG. 2

FIG. 3

FIG. 4

Fig. 1 is a front elevational view of a hinge clip for earrings showing my new design;

Fig. 2 is a side elevational view thereof;

Fig. 3 is a rear elevational view thereof; and

Fig. 4 is an end view thereof.

I claim:

The ornamental design for hinge clip for earrings, as shown.
